(57) **CLAIM**

The ornamental design for the hair clipper, as shown and described in the accompanying figures.

DESCRIPTION

FIG. 1 is a perspective view of a hair clipper according to the present invention;

FIG. 2 is a top end view of the hair clipper of FIG. 1;

FIG. 3 is a front view of the hair clipper of FIG. 1;

FIG. 4 is a side view of the hair clipper of FIG. 1;

FIG. 5 is a rear view of the hair clipper of FIG. 1; and,

FIG. 6 is a bottom end view of the hair clipper of FIG. 1.

The structures shown in broken lines in FIG. 1 are for illustrative purposes only and form no part of the claimed design.
